UNITED STATES PATENT OFFICE.

ALANSON McD. GRAY, OF ELIZABETH, NEW JERSEY.

CHILL-PLATE.

1,296,652.

Specification of Letters Patent. Patented Mar. 11, 1919.

Application filed August 3, 1916. Serial No. 112,942.

To all whom it may concern:

Be it known that I, ALANSON McD. GRAY, a citizen of the United States, residing in Elizabeth, in the county of Union, State of New Jersey, have invented certain new and useful Improvements in Chill-Plates, of which the following is a specification.

This invention relates to chill plates particularly applicable to that class of apparatus for molding wax and other material in which a series of narrow molds are set up in alternation with hollow chill plates, as exemplified in United States Letters Patent No. 653,235 granted to me July 10, 1900.

15 The invention relates particularly to certain improvements in the chill plates and method of circulating the water or other cooling fluid through them, whereby steady and uniform flow may be regulated and maintained and air pockets may be avoided. It also includes simple and effective means for discharging muddy and other deposits from the chill plates, as the same may from time to time accumulate therein.

20 In the accompanying drawings:

Figure 1, is a side elevation of a wax molding apparatus embodying the improved chill plates, partly in section, with some details omitted:

25 Fig. 2, a transverse section on line 2, 2, Fig. 1, showing one of the chill plates in section:

30 Fig. 3, an enlarged view of one corner of one of the chill plates, showing manner of connecting the cooling fluid pipes to the bottom thereof, and:

35 Fig. 4, a sectional view of some of the alternating molds and chill plates, on line 4, 4, Fig. 2.

40 The device in which the molds and chill plates are held in alternation may be a press of the filter press type, comprising a hydraulic cylinder 5, a movable head 6, fixed head 7, and side connecting bars 8. 9 indicates legs or supports for the press.

45 The molds 10 may be narrow open top frames provided with side ears 11 by which they are supported on the side bars 8. The chill plates are also provided with side supporting ears 12, as in my before mentioned patent.

50 It has been found that air pockets are liable to form in the circulating spaces or passages of chill plates heretofore used, and that adjacent such parts of the chill plates

the wax in the molds will be indifferently or unsatisfactorily chilled, resulting in more or less imperfections in the cake. This difficulty is remedied by, and other advantages accrue from, the improved chill plate of 60 this invention, which is constructed as follows. It is a narrow hollow plate, rectangular in form corresponding to the shape of the wax molds, or other receptacle to be submitted to cooling effects, and having side 65 walls 13, 13 and lateral partitions 14. The outer partitions extend from the top 15 to within a short distance from the bottom 16, and the intermediate one is connected to the bottom, its upper end being a short distance 70 from the top, as shown at Fig. 2. These chill plates with their supporting ears 12 are preferably made integral, as castings. The cooling fluid supply and discharge pipes pass up through the bottom of the chill plate to 75 within a short distance from the top in the end chambers or passages. The circulation of the fluid is downward from the inlet pipe 17, under the first partition 14, up and over the second partition and down and under 80 the third one, and upwardly to escape from the orifice of the discharge pipe 18, which is close to the top of chill plate. Water is generally used as the cooling fluid, its flow through the plates being for most purpose 85 quite slow to economize in the use of the water. To insure that all of the plates will be entirely filled and remain full with the water continuously moving it is found necessary, or very advantageous, to have the outlet orifice smaller than the inlet orifice; this may be accomplished by contracting the end 90 of pipe 18 into nozzle form as at 19, thus insuring that more water may enter the plates 95 through inlet pipes 17 than can escape therefrom. A smaller outlet pipe might accomplish a like purpose, but it is preferred to make the pipes of the same size and as large as possible, for a purpose that will hereafter appear. The pressure of the 100 water, or head under which it is supplied, is quite low and the flow through the plates is slow and variations in the quantities flowing through the various plates are, for various reasons, likely to occur. To provide 105 correction for this the pipes 17 and 18 are made vertically adjustable, and by setting their upper ends at suitable levels the flow through all of the plates may be made uniform and adequate to produce the desired 110

cooling effects in all of the molds. It may be necessary only to adjust one of the pipes, preferably the outlet pipe.

In the bottoms of each of the plates are fitted screw-threaded reducing plugs 20, 20, through the centers of which the pipes 17 and 18 are screwed so as to extend a distance below the plugs. This provides means for setting the upper ends of the pipes in proper working levels, and when so set they are securely held by jam nuts 21, 21. At and for some distance above the bottom of chill plates the pipes 17 and 18 are perforated with valve openings 23, which under ordinary working conditions are closed by the blank sides of sleeves 22, 22 closely fitting over the pipes. These sleeves are securely held in the plugs 20, 20 by being screwed therein, as shown, and they are provided with valve openings 24 arranged to align with the openings 23 when the pipes are rotated about one-half a revolution from the positions indicated in Fig. 3. Operating handles 25 are attached to the pipes 17 and 18 at or near their lower ends. The valves 23, 24 are set in open position when it is desired to drain water from, or to clean out the chill plates. In the latter case mud or other deposits may then be washed out by suitable flooding so as to fall into a trough 26. This trough is preferably formed of concrete. It is large enough to extend under the whole of the apparatus to receive and collect all water discharges whether from the discharge pipes 18 or leakage from any part of the apparatus. Each inlet pipe 17 is connected to a common water supply pipe 27 by means of flexible hose 28; this provides for permanent water connections to the chill plates, leaving them free to slide on the bars 8 as the press is manipulated to place the parts in operative position and to remove the chilled wax cakes.

Each bar 8 has a rail 29 secured to it by being fastened to bolted studs 30 extending from the sides of said bars. A carriage or platform truck 31 travels on the rails 29 being guided and supported thereon by grooved wheels or pulleys 32. This carriage 31 receives the cakes of set wax as they are removed from the molds, commencing at one end of the apparatus, receiving the wax cakes as they are removed from the successive molds and moved to or beyond the other end, as indicated in Fig. 1, to have its load of cakes taken away for packing. This saves considerable time required in the manipulation of the press.

33 designates a wax spout for filling the molds with melted wax. 34 is a drain pipe for the trough.

There is considerable advantage in connecting the inlet and outlet pipes of the cooling fluid to the bottoms of the chill plates. All liquid discharges fall under the

press out of the way leaving the sides of the press entirely free and unobstructive to the attendants operating the press. In my before mentioned patent the discharge pipes are at the side of the press and discharge 70 into a trough located also at the side of the press.

I claim:

1. A chill plate, comprising a horizontally narrow hollow vessel, a cooling fluid supply 75 pipe having an opening at its upper extremity, and located at one end of and extending through the bottom of said vessel, said open extremity terminating a short distance below the top of said vessel, a discharge pipe having an opening at its upper extremity and located at the other end of and extending through the bottom of said vessel, its open extremity terminating a short distance below the top of said vessel, 80 and means for vertically adjusting said pipes, whereby the flow of fluid through the vessel may be regulated commensurately with the head of the fluid supply.

2. A chill plate comprising a horizontally narrow hollow vessel having the same dimensions along any given side as along the side opposite thereto, a cooling fluid supply pipe, a discharge pipe, said discharge pipe being of less fluid conveying capacity than 90 said supply pipe, and both of said pipes extending upwardly through the bottom of said vessel, and means for vertically adjusting the said pipes, whereby the flow of fluid through the vessel may be regulated 95 commensurately with the head of the fluid supply.

3. A chill plate comprising a horizontally narrow hollow vessel provided with lateral vertical partitions with alternating openings at the upper and lower ends of the partitions, a cooling fluid supply pipe at one end of and extending through the bottom to within a short distance of the top of the vessel and terminating well above the opening of the first partition, a discharge pipe having its upper end reduced to a less area than that of the inlet pipe and located at the other end of and extending through the bottom to within a short distance of the top 105 of the vessel and terminating well above the opening of the last partition, and means for vertically adjusting the pipes, whereby the flow of fluid through the vessel may be regulated 110 commensurate with the head of 115 the fluid supply.

4. A chill plate comprising a narrow hollow vessel, a cooling fluid supply pipe at one end of and extending through the bottom to within a short distance of the top of the vessel, a discharge pipe at the other end of and extending through the bottom to within a short distance of the top of the vessel, a stationary sleeve surrounding the lower part 125 of each pipe, valve openings formed through 130

the pipes and sleeves, and means for vertically adjusting and rotating the pipes, whereby the flow of fluid through the vessel may be regulated commensurate with the head of the fluid supply and the valve openings alined to flush out and discharge sediment from the vessel.

5. A chill plate for wax molding apparatus, consisting of a narrow hollow rectangular vessel, an opening at each end of the bottom wall, a reducing plug screwed into each opening, a pipe held in and passing through each plug with its upper extremity perforated and terminating closely adjacent the top wall of the plate; means for vertically adjusting the pipes, and a jam nut on each pipe for securely holding it in adjusted position.

10. A chill plate for wax molding apparatus, consisting of a flat hollow rectangular vessel, an opening at each end of the bottom wall thereof, a reducing plug screwed into each opening, a pipe held in and passing through each plug with its upper end closely adjacent the top wall of the plate; a sleeve screwed into each plug and surrounding the pipe held therein, coacting valve openings through the pipes and sleeves and means for rotating the pipes to open and close said valve openings.

15. A chill plate for wax molding apparatus, consisting of a flat hollow rectangular vessel, an opening at each end of the bottom wall thereof, a reducing plug screwed into each opening, a pipe threaded into each plug and extending through it with its upper end closely adjacent the top wall of the plate; a sleeve secured to each plug and surrounding the pipe held therein, coacting valve openings through the pipes and sleeves, handles on the lower parts of the pipes, whereby the pipes may be vertically adjusted and the valves opened and closed, and jam nuts to lock the pipes in set positions.

20. A chill plate for wax molding apparatus, consisting of a flat hollow rectangular vessel, an opening at each end of the bottom wall, a reducing plug screwed into each opening, a pipe held in and passing through each plug with its upper end closely adjacent the top wall of the plate, the upper end

of one of the pipes being reduced to a less area than that of the other pipe; means for vertically adjusting the pipes, and a jam nut on each pipe for securely holding it in adjusted position.

25. A chill plate comprising a hollow elongated vessel, a cooling fluid supply pipe and a discharge pipe at the respective ends of said vessel, and valve means associated with said pipes at points inside said vessel for enabling flushing out and the discharging of sediment which may collect in said vessel through said pipes.

30. A chill plate comprising a hollow elongated vessel, a cooling fluid supply pipe and a discharge pipe extending through the bottom of said vessel at the respective ends of said vessel, said pipes being adapted to be rotated, and valve means associated with said pipes at points inside said vessel and brought into operation by the rotation of said pipes for enabling flushing out and the discharging of sediment which may collect in said vessel through said pipes.

35. A chill plate comprising a hollow elongated vessel, a cooling fluid supply pipe and a discharge pipe, said discharge pipe extending upwardly through the bottom of said vessel, at least one of said pipes being prolonged to within a short distance of the top of said vessel, a sleeve in said vessel surrounding and closely fitting the bottom portion of said prolonged pipe, there being relative movement of rotation between said sleeve and pipe, and both said sleeve and prolonged pipe having registrable valve openings.

40. A chill plate comprising a hollow receptacle provided with partitions extending vertically in opposite directions from one wall to a distance short of the opposite wall, inlet and outlet cooling fluid pipes passing in from the bottom of said receptacle at adjacent ends thereof and each extending to near the top of said receptacle.

45. In testimony whereof I have hereunto subscribed my name.
